UNITED STATES PATENT OFFICE.

RICHARD FISCHER, OF FRANKFORT-ON-THE-MAIN-RÖDELHEIM, GERMANY, ASSIGNOR
TO THE FIRM OF MAFAM MOTOR-APPARATE G. M. B. H., OF FRANKFORT-ON-THE-
MAIN, GERMANY.

MAGNETO APPARATUS.

1,131,931.

Specification of Letters Patent. Patented Mar. 16, 1915.

Application filed January 29, 1913. Serial No. 744,983.

To all whom it may concern:

Be it known that I, RICHARD FISCHER, a citizen of the German Empire, and a resident of Frankfort-on-the-Main, Rödelheim, Germany, have invented certain new and useful Improvements in Magneto Apparatus.

This invention relates to improvements in magneto ignition apparatus and has for its object to provide an ignition device, which, 10 besides having increased reliability as compared with magneto devices as heretofore constructed will insure a thorough ignition of the explosive mixture. Numerous attempts have been made to attain this result, 15 which attempts have, besides apparatus with automatic ignition devices, included the double type of apparatus, which type of apparatus has been found suitable on account of its manifold adaptability. Among such 20 constructions are some consisting of two single apparatus, arranged side by side, or one above the other. Such an arrangement partly possesses the advantage of an increased reliability and partly, by being mounted on an 25 ordinary base plate, that of economy of space.

The present invention aims to provide a magneto apparatus on an ordinary base plate and with a driving shaft, which will, 30 apart from its compact mounting, be an advance upon that heretofore proposed, particularly by reason of its high efficiency of ignition. The latter result is attained by 35 a parallel arrangement of two similar armatures in a common magnetic pole system, and by obtaining uniform distribution of the lines of magnetic force by the special shaping of the pole pieces.

The invention will now be described more 40 fully with reference to an example thereof shown in the accompanying drawings, in which—

Figure 1 is a diagrammatic sectional view illustrating the invention in its application 45 to pole pieces of ordinary construction, but showing the preferable arrangement of the two armatures geared together for rotation in opposite directions and at the same speed. Fig. 2 is a view similar to Fig. 1, but illustrating the preferred construction of pole piece with a parallel arrangement of the armatures.

Assuming the pole pieces as seen in Fig. 1 50 to be of rectangular cross section (with recesses for the space taken up by the arma-

ture) probably the lines of force would be distributed unevenly between the two armatures so that it would depend on the theoretical position of the magnetic poles to which of the two armatures the greater 60 number of lines of force would flow.

According to the present invention after having determined the position of the magnetic poles t^1 to t^4 with the existing construction of the pole casing, the pole pieces p^1 , p^2 of Fig. 2 are shaped, as for instance by cutting away portions a^1 , a^2 at one end to form isolated pole tips, so that their area of contact with the magnets, by allowing the requisite amount and position of air gap, insures a 70 practically equal length of path for the lines of force which are balanced by the two armatures.

The considerably increased efficiency of the improved device as compared with that 75 of other constructions can be readily explained by the fact that owing to the connection in parallel of the two paths of the lines of force the resistance of the unavoidable four air gaps when two armatures are 80 present is reduced in a manner which can be understood from the analogy of two electric resistances connected in parallel. Also the displacement of the field, which is caused by the opposite direction of rotation of the 85 two armatures at each break, favorably influences the force of the induction shock. The rotation of the two armatures in opposite directions, and at the same speed is effected, as indicated in Fig. 1, simply by directly 90 gearing them together by means of toothed wheels z^1 , z^2 . Moreover the stability of the magnet itself, especially when the two armatures are set at 90° apart is increased by the 95 fact that in no position of the armatures will the flow of the lines of force be materially interrupted.

It will be obvious that the apparatus can be employed as a two-spark magneto apparatus without a distributor for four-cylinder motors, and for motors, the cylinders of which are arranged at an angle, by a corresponding setting of the armatures as indicated in Figs. 1 and 2 respectively.

Now what I claim as new and desire to 105 secure by Letters Patent is:—

1. A magneto apparatus including a plurality of field magnets, a pair of oppositely arranged pole pieces, and a plurality of armatures operatively and permanently con- 110

nected for rotation together in opposite directions and at the same speed between the said pole pieces.

2. A magneto apparatus including a plurality of field magnets, a pair of oppositely arranged pole pieces cut away at one end to form isolated pole tips, and a plurality of armatures operatively and permanently connected for rotation together in opposite

directions and at the same speed between the said pole pieces.

In testimony whereof I have affixed my signature in presence of two witnesses.

RICHARD FISCHER.
